UNITED STATES PATENT OFFICE.

HENRY PARSONS, OF MARLBORO, MASSACHUSETTS.

BEAM-PRESSER.

No. 812,290.

Specification of Letters Patent.

Patented Feb. 13, 1906.

Application filed July 2, 1904. Serial No. 215,144.

To all whom it may concern:

Be it known that I, HENRY PARSONS, of Marlboro, in the county of Middlesex and State of Massachusetts, have invented certain new and useful Improvements in Beam-Pressers, of which the following is a specification.

This invention relates to beam-pressers.

Figure 1 in front elevation shows a machine constructed in accordance with my invention, parts of the framework being broken away to show the arrangement of my improved adjusting mechanism for the bed. Fig. 2 is an end elevation of a part of the machine, showing my improved adjusting mechanism. Fig. 3 is a cross-sectional view on the line 3 3 of Fig. 1 looking toward the bottom of the machine, showing the horizontal rod and the wing-nuts on the vertical rods. Fig. 4 is a detail view showing the connection between the horizontal rod and the vertical rod on each side of the machine. Fig. 5 is a detail view of the double-pawl ratchet carried by one of the vertical rods. Fig. 6 is a detail view of one of the wing-nuts.

1 represents the standard to the framework of a machine of the general type shown in United States Letters Patent No. 368,108, to which reference may be had for the general construction of the machine.

2 represents a girth or bed on which is arranged a series of blocks 3, that support the material to be cut or died out. In the practical operation of the machine it is necessary to adjust this girth up and down at different times. Prior to my present invention it has been the practice to adjust this girth up and down by means of a screw-rod on either side of the machine, as shown in said Patent No. 368,108. By this old method of adjustment it was necessary to adjust each end of the girth 2 separately, which operation involves considerable waste of time and calls for considerable calculation in order to secure uniformity of adjustment. By my present invention the adjusting mechanism is all tied together as a unit, so that both ends of the girth are adjusted simultaneously and uniformly. As shown, this adjusting mechanism consists of a horizontal rod 4, the ends of which are journaled in a lug 5 at either side of the framework.

6 and 7 represent vertical rods, the lower ends of which are journaled in the lugs 5, the upper ends being journaled in lugs 8 9, carried by the upper end of the framework, as

shown, the rod 6 being at one side of the machine and the rod 7 at the other. The ends of the girth 2 are formed with perforated lugs 10 11, the rod 6 being arranged in the perforation of the lug 10, while the rod 7 is arranged in the perforation of the lug 11, these lugs 10 and 11 being free to move up and down on their respective rods.

13 represents a beveled gear on the lower end of the rod 7, meshing with a complementary beveled gear 14 at the right-hand end of the horizontal rod 4. A similar gear 15 is secured to the lower end of the rod 6, meshing with a complementary gear 16 at the left-hand end of the rod 4.

17 represents a nut formed with wings 18. There is one of these nuts arranged on each rod 6 and 7, as shown, and engaging screw-threads 20 21 of said rods. The wings 18 engage planed ways on complementary vertical standards 23 of the framework, thus permitting the nuts 17 to move up and down on their respective rods without turning. As shown, the lugs 10 and 11 rest upon the nuts 17.

25 represents a double-ratchet-pawl mechanism secured to the upper end of the rod 7. By the operation of this pawl 25 in one direction the rods 6 and 7 will be turned and cause the nuts 17 to travel downward, thus lowering the girth 2, while a reverse motion of the ratchet-pawl 25 will turn the rods 6 and 7 in the opposite direction, causing the nuts 17 to travel upward, thus raising the girth 2.

By this construction the bed of the machine, consisting of the girth 2 and the blocks 3, can be readily and quickly adjusted to any desired height. If for any reason it is desired to adjust one side of the machine separately from the other, the gears 14 or 16, or both, may be slid inward on the rod 4 and the independent adjustment made, after which the gears can be returned to their normal position and secured in place in the usual way by the pins 30 or other locking means.

Having thus explained the nature of my invention and described a way of making and using the same, although without attempting to set forth all of the forms in which it may be made or all of the modes of its use, what I claim, and desire to secure by Letters Patent, is—

1. In a machine of the class specified, a vertically-adjusted bed-frame formed with a perforated lug at each end, stationary ways in each side of the framework in which said

lugs are arranged, a vertical screw-threaded rod arranged in each lug, bearings for each end of said rods connected to the framework and separate from said lugs or bed, a horizontal rod, a gear upon each end of said rod, a ratchet for turning one of said vertical rods.

2. In a machine of the class specified, a vertically-adjusted bed-frame formed with a perforated lug at each end, stationary ways in each side of the framework in which said lugs are arranged, a vertical screw-threaded rod arranged in each lug, bearings for each

end of said rods connected to the framework and separate from said lugs or bed, a horizontal rod, a gear upon each end of said rod, a complementary gear on the lower end of each vertical rod, one of the gears of said horizontal rod being mounted to be slid out of engagement with its complementary gear, and connections between said rods and said lugs.

In testimony whereof I have affixed my signature in presence of two witnesses.

HENRY PARSONS.
